UNITED STATES PATENT OFFICE.

ARMANDO RAGIONIERI AND OLINTO MADRIGALI, OF FLORENCE, ITALY.

SYSTEM FOR THE MECHANICAL ADJUSTMENT OF THE WICK IN SO-CALLED NIGHT LIGHTS AND NEW MEANS FOR FIXING THE WICK ITSELF.

Application filed July 18, 1922, Serial No. 575,911, and in Italy July 25, 1921.

The machine presented replaces the manual operation of threading; adjusting, cutting off and fixing the wick in the short candles commonly called night-lights.

The machine enables the advantageous variation of the wick-fixing method. The wick used, in fact, to be held fast by means of an underlying piece of metal, or clip, provided with lateral and central points, all turned in towards the interior or centre of the light; the lateral points served to hold the piece of metal in position, the central ones being intended to grip the wick. But the latter was not completely held fast because the points which are turned in toward the centre of the candle, even when flattened, failed to grip the wick.

With the new system, on the contrary, the central points turn outwards, and when the wick has been threaded in and the machine has flattened the points, the latter completely catch hold of the wick-end and grasp it tightly, even if forced upwards. The machine allows of the flattening of the points even if they are turned in towards the centre.

The machine consists in a member which draws the wick upwards, threading it into the centre of the candle and adjusting the height thereof, in a cutting-off system at an appropriate and adjustable point of the wick itself; and in a device for compressing the points of the piece of metal serving to fasten the wick; the whole being caused to act by a single operation or by two distinct operations.

The accompanying drawings show two practical examples of the application of the invention. Therein, Fig. 1 is a front view of the mechanism, as a whole; Fig. 2 is a plan of said mechanism; Fig. 3 the same apparatus, partly in section, represented as when at work; Fig. 4 the plan of the apparatus, likewise, when at work, but for clearness in the drawing, without the operating lever. Fig. 5 shows in vertical section and in horizontal section, respectively, a system for enabling a wheel of the apparatus to be displaced so far as to allow the wick to pass through. Fig. 6 shows the plane projection of the counter-weight with its adjusting-screw; Fig. 7 a system of brake for the fore wheel, and Fig. 8 is the metal piece, which when applied to the bottom of the candle, holds the wick fast.

Figs. 1-7 are examples of the first type of machine.

The second type is indicated by Figs. 9-15 therein. Fig. 9 indicates a side view of the apparatus; Fig. 10 shows the latter in a plan view and Fig. 11 is a front view. Fig. 12 is a section on line A-B of Fig. 10; Fig. 13 a cross section on line C-D of Fig. 12; Fig. 14 is likewise a cross section, on line E-F of Fig. 12; Fig. 15 likewise a cross section, on line G-H of Fig. 12.

The variations in connection with the second type relate to a rubber band applied to the wheels which raise the wick, which band or cover affords the advantage of additionally assuring the raising of the wick itself. Moreover, said wheels have been provided with a plate which may be fixed at various points and against which strikes a catch; thus, by a variation in the position of the plate the length of the wick is varied.

The hammer for the purpose of flattening the clip, is in this second type, adjustable in respect of its height, it being screwed fast.

The second example presents a type with operations independent of each other, so that, at one stroke; movement is imparted to the wheels in order to raise the wick, whereas the operation for cutting off the wick and flattening the clip is brought about at another stroke, although with the same hand.

The machine consists in a support —a— adapted to fasten it to any plane surface. From the support —a— depend two pairs of forks —b—c— which sustain, respectively, an axis —d—e— on which are pivoted two slightly grooved wheels —f—g—. To said wheels are affixed two intermeshing gears —h—i—, so that they are enabled to turn together.

The pivot —d— of the rear wheel —f— is rigid with said wheel and plays in the apertures of the fork —b—. The play is such as to allow of the displacement of the axis —d— such as to enable the passage of a wick of greater or less thickness in the grooves of the wheels —f—g—. So that the wheel may not play by jerks, but smoothly, a band spring —k— is located appropriately between the axis —d— and the forked support —b— (see detail in Fig. 5).

Instead of the spring —k— the aperture for the grooved axis may be made slanting,

so that the weight of the wheel f allows of a slight displacement of the wheel itself.

Above the support a is located a column 1^a within which slides the bearer m of the lever n . Said bearer may be adjusted as to height by means of a small vise (or binding-screw o).

The lever n carries a hammer p which serves for the flattening of the metal part supporting the wick of the candle.

The lever n carries, pivoted to one end thereof two small connecting rods q — q — which encircle a small counter weight lever r to which are pivoted the two supporting arms s — t pivoted to the same axis e of the wheel g . From this construction it will be seen that when the lever n is depressed, at the beginning of its downward motion, it will rock the lever r on its pivot and thus force it into frictional engagement with the wheel g , whereupon the further depression of the lever n will cause the wheel to rotate until said lever has reached the limit of its downward motion, at which time the lever r will have been swung into the position shown in Fig. 3. During the upward movement of the lever n , the lever r will not rotate the wheel backward because, owing to the position of the lever, there is not sufficient frictional contact between it and the wheel to overcome the breaking action of the member 7.

The lever r , in its turn, is provided with a regulating screw u which serves to regulate the course of the wheel and consequently, the length of the wick. The lever n is provided at one end with a draw spring w . Between the two wheels, at the lower part of the support, is situated a guide member x into which passes the wick, it being guided and threaded into the nozzle y which carries a seat within which rests—always at the same point—the candle.

Between the base z and support a is situated a groove 1 within which plays a knife 2 which is moved by the end 3 of a lever 4 upon which acts a pin 5 secured to the lever n . A small spring 6 conveys the knife back to its place when the lever n is raised.

In order that the fore wheel may not revolve in a contrary direction, within the support a is located a small brake, formed by a pin (or pivot) 7 with a small piston round the rod of which is wound a spiral spring which forces down the pin itself, causing friction against the wheel g .

With said machine the small metal disc 8 may be used for supporting the wick. This part, thereby differing from those already in use, carries the lateral points turned in towards the center of the candle and the central ones 10 outwards. This inno-

vation affords the advantage, already alluded to, of ensuring the complete gripping of the wick, because the flattened points, owing to their tendency to turn outwards, while drawing the wick, cause that end of the latter which is held fast to always tend to catch into the points which have gripped the wick.

The operation of the apparatus is as follows:—After inserting the wick into the open space or curve between the wheels and having introduced it into the aperture of the part x the candle to which the small metal disc 8 has already been applied, is placed upside down, on the base z . Then the lever n is lowered at a single stroke, carrying with it the wheel g which is made to revolve to a certain extent corresponding to the length of the wick which is, meanwhile, threaded into the candle and raised therein, because it is drawn up by the action of the two wheels g — f . As soon as, after traveling a very short distance, the wick reaches the central aperture of the small disk 8 already applied to the candle the hammer p , at this point, strikes, and presses against the points 10 , flattening them and thus catching into the wick. At the same time, the small pin 5 strikes against the lever 4 which inclined and impels with its lower part, the knife 2 which cuts clean through the wick, leaving out as much as is required for ignition.

As soon as the lever n is released, through the action of the counter-weight v and of spring w it rises again and thus the knife returns to its place, through the action of its spring 6 and the regulating screw u applied to the lever r is urged against the base a of the apparatus, again setting it in position for a fresh operation. From now, the wick remains constantly fast, and the candles are set, manually, in the seat of the base z . The cuttings produced by clipping the wick are collected in the groove 1 and driven out, one after the other.

In the example shown in Figs. 9—15 it will be seen that the wheels f — g — are provided with a band or rubber cover 11 , applied in any manner around that portion of their periphery which is not toothed. The wick finds itself between this rubber band, and by the application thereof it is more readily induced to rise and find room, whatever its size. In order to locate the wick with precision, it is inserted into the guide 12 supported by the columns 13 , fixed to the base a . In such manner the wick carried by the rubber band of the wheels and which winds off an underlying reel is completely introduced into the aperture of the part x . The reel not shown in the drawing because it is a common part has a wide diameter which prevents the crum- 130

bling of the wax surface of the wick wound round said wheel, which is thus contained in large quantities in the reel itself.

The operation of the wheels *f*—*g*— is rendered independent and is effected by the levers *14*—*15*— pivoted on the pivot of the wheels *f*— and united at the upper part by a lever-catch *16*— which is depressed by the finger and in which the enlarged part *17*—, by pressing on the rubber of the wheels, compels them to turn. In this form of the device, a spring *w* directly engages the levers *14* and *15* and serves to return them to initial position, this spring being used in place of the spring *w* which in the form of the device first described is shown secured to the lever *n*.

The lever *14*— is provided with a nose *18*— which on striking against the small plate *19*— limits the run of the wheels *f*—*g*—.

Said small plate *19*— is provided with a groove into which enters the screw *20*—.

Manifestly, the small plate may be raised and lowered, thus increasing or diminishing the run of the wheel and, therefore, the length of the wick.

The small hammer *p*— is formed by a screw which passes through an enlargement *21*— of the lever *n*—. Said hammer is provided with two check-nuts *23*—*24*— which secure the hammer *p*— in the desired position.

In this example the column *1a*— carries pivoted at *m*— the lever *n*—, without the part *m*— being slidable, as in the first example.

The device which strikes against the lever *4*— for cutting of the wick, consists in a roller *25*— rather than in the screw *5*—. Said roller acts like the screw *5*—.

The operation of the flattening the clip remains the same as in the first example, that is to say, that on the lever *n*— being lowered with the small hammer *p*— adjusted, the desired effect is obtained.

Claims:

1. A machine of the character described, comprising, in combination, a base, a pair of intermeshing wheels mounted for rotation on said base and adapted to grip a wick between them, a member pivoted in concentric relation with one of said wheels and adapted when moved in one direction to frictionally engage said wheel, means for actuating said member thereby to rotate the wheel a predetermined distance, and means automatically operative to return said actuating means to initial position.

2. A machine of the character described, comprising, in combination, a base, a pair of intermeshing wheels mounted for rotation on said base and adapted to grip a wick between them, a movable member adapted when moved in one direction to frictionally

engage one of said wheels, means for actuating said member thereby to rotate said wheel a predetermined distance, a knife carried by said base and slidable into position to sever said wick, a spring for retaining said knife in inoperative position, and means actuated by said actuating means for imparting sliding motion to said knife against the tension of its spring.

3. A machine of the character described, comprising in combination, a base, a candle-supporting member carried by said base, the base having a wick aperture concentric with said member, a pair of intermeshing wheels mounted for rotation on said base and adapted to grip a wick between them, means for rotating said wheels a predetermined distance in one direction thereby to feed said wick, and a guide member carried by the base and adapted to receive the wick from said wheels and deliver it to said candle-supporting member.

4. A machine of the character described, comprising, in combination, a base, a candle-supporting member carried by said base, the base having a wick aperture concentric with said member, a pair of intermeshing wheels mounted for rotation on said base and adapted to grip a wick between them, means for rotating said wheels a predetermined distance in one direction thereby to feed said wick, a guide member carried by the base and adapted to receive the wick from said wheels and deliver it to said candle-supporting member, a knife mounted on the base in spaced relation to said candle-supporting member and slidable into position to sever said wick, and means operable by the actuation of the wheel-rotating means for imparting sliding motion to said knife.

5. A machine of the class described, comprising, in combination, a base, a pair of intermeshing wheels mounted for rotation on said base and adapted to grip a wick between them, a pair of arms pivoted in concentric relation to one of said wheels, a lever pivoted to said arms and adapted when swung on its pivot to engage said wheel, an operating lever pivoted on the base, rods connecting said levers together whereby when said operating lever is swung on its pivot the wheel-engaging lever is swung into operative engagement with the wheel thereby to rotate said wheel in one direction a predetermined distance, and means for returning said levers to initial position.

6. A machine of the character described, comprising, in combination, a base, a pair of intermeshing wheels mounted for rotation on said base and adapted to grip a wick between them, a pair of arms pivoted in concentric relation to one of said wheels, a lever pivoted to said arms and adapted when swung on its pivot to engage said wheel, an operating lever pivoted on the base, rods

- connecting said levers together whereby when said operating lever is swung on its pivot the wheel-engaging lever is swung into operative engagement with the wheel thereby to rotate the latter a predetermined distance in one direction, a knife carried by said base and slidable into position to sever said wick, a spring for retaining said knife in inoperative position, and means actuated by said operating lever during its pivotal movement for imparting sliding motion to said knife against the action of its spring. 60
7. A machine of the character described, comprising, in combination, a base, a pair of intermeshing wheels mounted for rotation on said base and adapted to grip a wick between them, a candle-supporting member carried by said base, the base having a wick aperture concentric with said member, means for rotating said wheels a predetermined distance in one direction thereby to feed said wick, a guide member carried by the base and adapted to receive the wick from said wheels and deliver it to said candle-supporting member, a wick-gripping member supported in said supporting member, a knife mounted on the base in spaced relation to said candle-supporting member and slidable into position to sever said wick, means for imparting sliding motion to said knife, and a lever pivoted on said base and adapted to operate said rotating means, said wick gripping means, and said knife-operating means in proper sequence during pivotal movement of the lever in one direction. 65
8. A machine of the character described, comprising, in combination, a supporting member having a guide opening, means for feeding a flexible wick through said opening, said supporting member being adapted to support a wick-gripping member having a wick receiving opening in alinement with said guide opening provided with a set of pointed projections extending at an angle therefrom around its periphery and a similar set of projections around said wick opening, means for actuating said feeding means, and means carried by said actuating means 70
- for bending the projections of one set toward those of the other set. 66
9. A machine of the character described, comprising, in combination, a supporting member having a guide opening, means for feeding a flexible wick through said opening, said supporting member being adapted to support a disk having a wick receiving opening in alinement with said guide opening and provided with a set of pointed projections extending at an angle from the disk around said wick opening, means for actuating said feeding means, and means carried by said actuating means for bending said projections toward the periphery of the disk. 75
10. A machine of the character described, comprising, in combination, a support, a pair of wheels mounted for rotation on said support, each of said wheels divided along its periphery into a toothed portion and a smooth portion, the toothed portions being in intermeshing relation, a friction band encircling the smooth portion of each wheel, means for rotating one of said wheels a predetermined distance in one direction, a guide member carried by said support in position to receive a wick fed between the smooth portions of the wheels, and means for manually operating said wheel rotating means. 80
11. A machine of the character described, comprising, in combination, a support, a pair of wheels mounted for rotation on said support, each of said wheels divided along its periphery into a toothed portion and a smooth portion, the toothed portions being in intermeshing relation, a rubber band encircling the smooth portion of each wheel, means for rotating one of said wheels a predetermined distance in one direction, a guide member carried by said support in position to receive a wick fed between the smooth portions of the wheels, and means for manually operating said wheel rotating means. 85

In testimony whereof they have signed their names to this specification.

ARMANDO RAGIONIERI.
OLINTO MADRIGALI.
